Claims priority, application Cuba May 25, 1944

4 Claims. (Cl. 159—26)

1

This invention relates to evaporating apparatus and more particularly to apparatus of multiple effects used for concentrating solutions by the evaporation of their solvents, as is done with sugar solutions in the manufacture of sugar. It is known that those apparatus comprise various units operating at pressures progressively lower and successively run over by the operated liquid from the unit of highest pressure to the unit of lowest pressure, wherein the product vapors of any unit except the unit of lowest pressure are applied as heating agent in the immediate unit of lower pressure.

It is an object of the invention to provide a unit comprising a lower evaporating calandria constituting an emulsifier of the operated liquid and mounted on the top of that emulsifier a main calandria in which the operated liquid penetrates at its outlet from the lower calandria emulsified with a great amount of steam, whereby the evaporating capacity of said main calandria is considerably increased.

It is a second object of the invention to provide means for emulsifying the operated liquid at the inlet of every one of the tubes of the lower calandria by virtue of a steam injection from an outside source.

It is another object of the invention to provide a unit of the type described in the preceding paragraph, comprising complementarily a heater surrounding the emulsifier and arranged within to cause the liquid being passed therethrough to take a circuitous path whereby the liquid will be brought to a temperature near to the normal operating temperature of the emulsifier before the liquid is passed to the emulsifier proper.

It is still another object of the invention to provide appropriate diaphragms both in the calandrias of the evaporating units and in the complementary heaters in order to transform those calandrias into a circuit run over by the heating fluid, wherein the cross section of that fluid decreases progressively in order to maintain a sufficient fluid speed.

It is a well known fact that the efficiency of heat transfer from the steam in a calandria jacket to the liquid contained in the calandria tubes is greatly increased by the presence in the liquid of a substantial quantity of steam. The steam within the tubes tends to form a central core which forces the liquid in a thinned out manner against the tube walls. This is known in the art as climbing film effect.

In prior evaporators, however, no provision has been made to assure the realization of the climb-

2

ing film effect from end to end of the tubes of a calandria. There is generally some reduction of pressure of the liquid as it enters or approaches the tubes, which causes the liquid to reach the tubes in a super-heated condition. It might be supposed that this would immediately result in the spontaneous generation and release of an ample quantity of steam within the tubes but, in point of fact, the release of steam is uncertain and inadequate under actual operating conditions, so that the climbing film effect is likely not to be effectively realized until after the liquid has progressed a considerable distance upward along the tubes. This results in a loss of heating efficiency.

In order to overcome this deficiency there is provided, in accordance with the present invention, in connection with the evaporating calandria of each effect or unit, a comparatively small auxiliary or emulsifying calandria through which the liquid en route to the main calandria is first passed in order that the liquid arriving at the tubes of the main calandria shall be thoroughly emulsified with steam generated within the tubes of the emulsifying calandria.

The number of tubes in the emulsifying calandria may be comparatively small as compared with the main calandria, because the volume of the combined liquid and steam is greatly increased in the passage through the lower calandria tubes, and is again greatly increased in the passage through the upper calandria tubes. By providing fewer tubes in the lower calandria the velocity of the liquid and steam through the lower calandria is held within limits of the same order of magnitude as the velocity of the liquid and steam through the upper or main calandria tubes.

It is desirable that emulsifying steam be injected from an outside source at the entering ends of the emulsifying calandria tubes, in order that the climbing film effect may also be realized from beginning to end of the emulsifying calandria tubes. This may be achieved at a small expense of injected steam because of the comparatively small number of tubes in the emulsifying calandria.

The mixed liquid and steam which emerge from the lower calandria tubes enter a closed, solid-walled steam-tight chamber, which extends from the discharge ends of the tubes of the lower calandria to the entering ends of the tubes of the upper calandria and which communicates exclusively with the upper and lower calandria tubes. The chamber is sealed off completely

from communication with the steam jacket of the upper or main calandria, and is unrestrictedly open from end to end to provide direct and free communication between the tubes of the lower calandria and the tubes of the upper calandria, whereby the chamber inescapably confines all the liquid and the steam emerging from the tubes of the lower calandria and causes them in their entirety to be delivered together at substantially undiminished pressure and temperatures to the tubes of the upper calandria where they achieve a climbing film effect from end to end of the numerous upper calandria tubes. Means are provided for supplying both the upper and the lower calandria jackets with heating steam of pressure and temperature substantially higher than the pressure and temperature existing within the lower calandria tubes, in order to produce efficient heat exchange through the tube walls of both calandrias.

For other objects and for a better understanding of the invention, reference may be had to the following detailed description taken in connection with the accompanying drawing in which

Fig. 1 is an elevational view of a unit embodying features of the present invention and comprising an annular heater.

Fig. 2 is a vertical sectional view of the unit illustrated in Fig. 1.

Figs. 3, 4 and 5 are respectively horizontal cross-sectional views of the emulsifier and heater of the same unit and taken at stations 3—3, 4—4, and 5—5, of Fig. 1.

Fig. 6 shows a development of the annular heater about the emulsifier of said unit, illustrating the directional flow of the heating vapor therethrough.

Fig. 7 is a vertical cross-sectional view of a unit which does not comprise an annular heater.

Figs. 8, 9 and 10 are horizontal cross-sectional views taken through the emulsifier at stations 8—8, 9—9 and 10—10 of Fig. 7.

Referring now particularly to Figs. 1 to 5, the unit represented includes an emulsifier CE, having an annular heater U and a central calandria CI having vertically-extending tubes Q' and a main calandria M₁ mounted on the emulsifier. The function of the annular heater U is to provide the initial heat to the solution while the function of the central calandria is to bring about the emulsion of the solution. The annular heater U is made in the customary form, in groups of three tubes Q operating in parallel and the solution under treatment and on each pass up and down the heater is distributed among these three tubes. It is understood, of course, that any number of these tubes can be used. A group of three tubes is contained in each of spaces Qs, Fig. 4, within the annular heater U. The heating vapor is passed through all these spaces Qs successively in a manner hereinafter disclosed.

The solution being treated circulates successively through all these groups of three tubes Q of the heater, alternately in one vertical direction through one group and then in the other vertical direction through another group. This effect is attained by connecting two successive groups with end channels C in the lower and upper heads D₁, D₂. All of the channels C of each head are isolated from one another.

The solution being treated is thus circulated through all groups of tubes and all the channels of the lower and upper heads, entering through pipe GD, Fig. 5, and leaving through a space e to

enter into the bottom ends of the tubes Q', of the central calandria CI, Fig. 2, from a circular space I₀ thereunder.

Closing the bottom of the circular space I₀ is a nozzle Y with numerous spouts I, respectively aligned with open bottom ends of tubes Q'. The medium or vapor for treating the liquid enters the nozzle Y through the tube S and leaves the nozzle Y through the several vertical spouts I and then upwardly in space I₀ to the tubes Q'.

In this manner, the solution which arrives at the upper part of said circular space I₀ enters the tubes Q' at the same time as the injected vapor used to emulsify it. Having heated the calandria in a manner to be later described, the injected vapor is augmented by the vapor produced by partial evaporation of the liquid being treated inside the tubes Q' themselves. In this manner, by the time the treated liquid reaches the bottom F of the main calandria, it has become highly emulsified and conditioned to absorb the greatest amount of heat.

With steam issuing from said spouts and into the bottom open ends of the tubes Q', the steam will occupy the center of the tubes and the liquid being so treated is forced in a thinned out manner against the tube wall, whereby the liquid is more readily heated by the heating fluid passing externally about the tubes. Accordingly, the amount of heat transmitted to the liquid is increased, and a more effective evaporating unit is provided.

Calandria and annular heater U are supplied with heating medium through pipes St and T₁. The heating medium from T₁ before going through annular heater U, Fig. 2, first passes through the central calandria CI by way of passageway a which fans out vertically as it approaches the central calandria space CI so as to distribute the vapor throughout the entire height of the calandria. Inclined walls V and V' constitute the upper and lower sides of the passageway a. The vapor which comes through the passageway a is thus distributed throughout the entire height of the calandria, goes through the central calandria CI diametrically and leaves through passageway b at the opposite side thereof, Figs. 2, 4, 6.

The tubes Q' inside the central calandria CI are distributed somewhat irregularly, Fig. 5, but arranged so that resistance to the passage of the heating medium or vapor through the calandria from its entrance up to its outlet, may be fairly much the same and so that whatever path that the vapor may take among the tubes, there is assurance that the movement of the vapor is fairly equally distributed throughout the entire calandria, thereby avoiding any dead area therein.

Upon arriving at b, the heating medium or vapor is divided into two currents, Fig. 6. One of these currents goes through the spaces Qs on the right, entering from b and passing to a space adjacent passageway a, and the other current goes through the spaces Qs on the left, from b and passing to a space adjacent the passageway a.

Upon arrival in the last spaces on opposite sides of passageway a, the currents are united by entry through the openings f and g into spaces K₀, L₀, above and below the inlet passageway a and walls V and V'. The high openings f pass the noncondensable gasses and uncondensed vapor to the space K₀ while the low openings g pass the condensed vapor or water. The non-conden-

sable gases combined with the uncondensed vapor are removed from the space K_0 through the tube K and the condensed water is removed from the lower space L_0 through the tube L .

The small openings or apertures $d_1, d_2, d_3, d_4, d_5, d_6$, etc. and $d'_1, d'_2, d'_3, d'_4, d'_5, d'_6$, etc. Fig. 6 are provided in the walls or partitions P_l between the respective several spaces Q_s for the purpose of passing the fluid from one space to the other. The total area of the openings is greater for a wall at the points of movement where the amount of vapor being passed is greater and small at the points of movement as in the last spaces where the amount of vapor is less. In other words, movement of the vapor or heating medium from b to a , whether through the right spaces or the left spaces, the vapor goes from one space to the next through limited apertures whose total section is decreased each time in proportion to the progress of the condensation and in such a manner that its velocity is not excessive at the beginning of the passage nor too low at the end thereof.

Referring now particularly to Fig. 6, where the heater is represented in development, with the passageway b in the center. A group of three tubes Q of one space is represented by a single vertical tube Q contained between two vertical walls P_l , which separate the space from the adjacent spaces. The upper and lower heads D_s, D_i , are angularly adjusted with respect to each other in an amount equal to half a channel or return passage C so as to connect two adjacent groups of tubes together. The channels C are rounded as shown and contain a metal cylinder J which directs the stream of the treated liquid in this passage from one group of tubes of one space to the group of tubes of the next space, so that the movement of that stream is more or less circular within the channel and thus the possibility of pressure loss caused by change in direction of flow of the liquid is inhibited. The various tubes Q, Q' , are supported in and extend through upper and lower closure plates P_s and P_i at their respective opposite ends thereof. The plates are held in place by heads D_s and D_i .

The vapor which goes from b to the spaces immediately adjacent thereto, enters the first space through five apertures d_{11}, d'_{11} in the first wall P_l , which separates b from that space. The next walls which separate the first spaces from the second have five apertures d_{10}, d'_{10} , arranged in staggered relation to the five apertures in the first wall. Confining the description to the left side, the following two walls on that side have respectively four and three apertures d_9, d_8 , staggered to one another. The next walls have, respectively, four openings d_7 , three openings d_6 , two openings d_5 , two openings d_4 , three openings d_3 , two openings d_2 , one opening d_1 and the final wall, the openings f, g , as above described. A corresponding arrangement of apertures is provided in the walls at the opposite side of the heater.

The vapor paths are generally decreased in number within the successive spaces in passing from b to the spaces K_0, L_0 . As a result of successive condensations the steam vapor is reduced to its non-condensable gases which are removed from said container through the tube K . It is to be remembered that the dimensions of the successive apertures are not all equal, since it is preferable that they be adapted to the volume of the vapor passing through them. The number of

apertures is determined by the necessity to avoid excess velocity of the vapor in the first spaces to prevent substantial pressure loss in that vapor, and also by the necessity to maintain sufficient velocity in that vapor at the end to get a transmission of heat to the heated tubes Q and removal of the non-condensable gases.

On the top head D_s is disposed the main calandria M_1 , Fig. 2. This is effected by means of a neck-shaped casting A carried on the top thereof and supporting the calandria bottom F . The neck casting A is secured to the top head D_s by a packing nut P .

The main calandria M_1 includes a heater section Z , Fig. 2, containing a plurality of vertically extending pipes z in communication with basin F and the top of the main calandria, and through which the liquid being treated is passed. Neither the entrance of the heating vapor, nor the circulation of that vapor in the calandria, nor the outlet of its condensates and of the uncondensed residue are shown in the figure because the description of the two types of lower calandria and of the heater annexed to the first are sufficient for relating all the features of the invention. Vapor formed by the treated liquid is salvaged and taken from the top of the main calandria for delivery to the succeeding unit. The emulsifier of second, third and fourth units may be heated by vapor other than that supplied by preceding main calandrias. For example, they may be heated by the vapor that heats the first unit.

In every unit or effect the lower, emulsifying calandria is made to contain only a few tubes so compared with the associated upper, main calandria of the same unit. This causes a greater evaporating space to be provided in the upper calandria, making it possible to transmit all the steam from the lower calandria tubes, along with the liquid, into the upper calandria tubes, without producing a detrimentally high velocity of the liquid and steam in the upper tubes as the steam content of the upper tubes goes on increasing. The really important amount of evaporation takes place in the numerous tubes of the upper calandria. The function of the emulsifying calandria is to produce enough steam for assuring that the liquid will reach the main calandria sufficiently emulsified with steam to assure maximum efficiency of operation of the main calandria. For this purpose a comparatively small emulsifying calandria is adequate. A larger emulsifying calandria would add to the cost of the apparatus and would produce no corresponding gain of efficiency.

The emulsified liquid passing up through the heater Z is drained off through a central pipe B with a reducing fitting E therein and delivered to the emulsifier of the next unit for further treatment through a pipe G_{C_1} .

In Figs. 7, 8, 9 and 10, the lower part of a unit having no annular heater is shown. That arrangement is adopted generally in the units of an evaporating apparatus other than the first, because the concentrated liquor of the preceding unit which feeds the succeeding unit is easily maintained in a superheated state and does not require the above described annular heater U of emulsifier C_E , as the first unit of an evaporating apparatus of multiple effect.

In order to bring about proper heating in these units, the vertical calandria is divided into four spaces by radial walls $P'_{l_1}, P'_{l_2}, P'_{l_3}, P'_{l_4}$, having respectively, window openings d'_1, d'_2 , etc. therein. The horizontal sectional area of these

spaces diminishes in proportion to the decrease in volume of the vapor which goes through them, Fig. 9, so as to maintain the velocity of the vapors inside the calandria fairly constant.

Recovered vapor is brought from the main calandria of the preceding unit and is delivered to the emulsifier inlet T'. Within the emulsifier E', it passes from the larger spaces, Fig. 9, to the smaller space. Outlet pipes, not shown, corresponding to pipes K and L of the unit of Fig. 2, may be connected to the smaller space for taking off respectively the non-condensed gases or vapors and the water condensate.

The connections of the emulsifier E' to its main calandria is only slightly different in Fig. 7 than in Fig. 2. The neck casting A' is supported upon flanged upper end of the emulsifier casting, and packing nut P' is used for connecting the supporting basin F' thereto. Drain pipe E' extends down from the main calandria through the emulsifier E' for delivery to a pipe G'c'.

I have described what I believe to be the best embodiments of my invention. I do not wish, however, to be confined to the specific embodiments shown, but what I desire to cover by Letters Patent is set forth in the appended claims.

I claim:

1. In an evaporating unit, an emulsifier having a vertical calandria with tubes therein through which fluid being treated is passed, an annular heater surrounding the emulsifier calandria and having a plurality of vertically-extending wall partitions to provide spaces for the passage of heating vapors therethrough, tubes extending respectively through the heater spaces, a head member having return passages at the upper and lower ends of the heater and tubes to direct the flow of liquid being treated from the tube of one space to the tube of another space thereby to cause a circuitous path for the liquid traversing the heater, a fluid connection between the outlet end of the heater and the calandria for directing the fluid from the heater into the tubes of the emulsifier calandria, an inlet for directing heating vapors into the emulsifier calandria and over the tubes thereof, fluid connection between the calandria and the heater adapted to receive the heating vapors leaving the emulsifier calandria and directing the same in two directions through respective halves of the annular heater, said wall partitions of the heater having openings for the passage of the heating medium from one space to an adjacent space, the said wall partition openings varying in number in the respective wall partitions, and the opening of adjacent partitions staggered with respect to each other, the larger number of openings being in the walls nearer to the part of the heater first receiving the heating vapors from the vertical calandria and the smaller number of openings being in the walls nearer the end of the heating paths, whereby the velocity of the heating medium is retained constant throughout the annular heater.

2. A unit of evaporating apparatus comprising an upper calandria of parallel tubes and a lower calandria of parallel tubes having at one of its extremities a liquid supply chamber in free and open communication with the inlet ends of the tubes of that calandria; at its other extremity a closed chamber located between the calandrias, said chamber connecting the outlet ends of the tubes of the lower calandria directly and freely with the lower ends of the tubes of the upper

calandria; the lower calandria containing a less number of tubes than the upper, an annular heater surrounding the lower calandria, said heater including a plurality of groups of vertical tubes, each of these groups constituted by an equal number of tubes all of the same diameter and of the same length, located at the same level and the same radial distance from the center of the lower calandria around that center; a plurality of closed channels in the upper end of the heater and a plurality of closed channels in the lower end of the heater and in each of which arrive the outlet ends of a group of tubes and the inlet ends of the following group, except a first channel where instead of outlet ends of an entering group there is provided the outlet of a pipe which introduces the relatively cold liquid to be treated, and a last channel where instead of inlet ends of a following group there is provided an opening placing that channel in communication with the liquid supply chamber of the lower calandria, in order to constitute a long circuit run over by that liquid.

3. In a unit of evaporating apparatus having a calefaction chamber that surrounds tubes for material to be heated, the arrangement that consists in dividing the calefaction chamber in sectors by means of vertical and radial divisions, the successive divisions having openings so aligned that the heating vapors are compelled to travel lengthwise of the sectors, except one division that occupies at all its height the whole vertical radial section corresponding to the chamber and is unprovided with openings; there being located in the sectors adjacent to that division, respectively at one side and the other of the same, the entrance of the heating fluid and the outlet of its residual vapors and gases in order to create a circuit run over by the heating vapor from its entrance to its outlet, the cross-section of the vapor path being progressively decreased from sector to sector in accordance with the diminution of volume of the fluid which results from the condensation of the vapor flowing through the paths, by making the angular distance between successive divisions diminish from sector to sector according to the direction of the movement of the heating fluid.

4. A single unit of evaporating apparatus comprising, in combination; an upper main calandria which includes substantially vertical liquid evaporating tubes and a heating steam jacket surrounding the tubes; a lower emulsifying calandria which includes liquid evaporating tubes, a heating steam jacket surrounding the last mentioned tubes, and a liquid supply chamber in communication with the inlet ends of the tubes; a closed, solid-walled steam-tight chamber extending from the discharge ends of the tubes of the lower calandria to the entering ends of the tubes of the upper calandria and communicating exclusively with the upper and lower calandria tubes, said steam-tight chamber being sealed off completely from the upper calandria steam jacket, and being unrestrictedly open from end to end to provide direct and free communication between the tubes of the lower calandria and the tubes of the upper calandria, whereby said steam-tight chamber inescapably confines all the liquid and the steam emerging from the tubes of the lower calandria and causes them in their entirety to be delivered together at substantially undiminished pressure and temperature to the tubes of the upper calandria; and means supplying to both the lower and upper

calandria jackets heating steam of pressure and temperature substantially higher than the pressure and temperature existing within the lower calandria tubes in order to produce efficient heat exchange through the tube walls of both calandrias; the tubes of the upper, main calandria being several times as numerous, at least, as the tubes of the lower, emulsifying calandria to provide a greater evaporating volume in the upper calandria; thereby achieving a climbing film effect from end to end of the upper calandria tubes.
